UNITED STATES PATENT OFFICE

ALEXANDER ADAMSON, OF AKRON, OHIO.

COLLAPSIBLE CORE.

1,177,755.

Specification of Letters Patent.

Patented Apr. 4, 1916.

Application filed January 7, 1915, Serial No. 974. Renewed February 21, 1916. Serial No. 79,797.

To all whom it may concern:

Be it known that I, ALEXANDER ADAMSON, a citizen of the United States, residing at Akron, in the county of Summit and State of Ohio, have invented new and useful Improvements in Collapsible Cores, of which the following is a specification.

This invention relates to improvements in collapsible cores for the manufacture of tire shoes or casings of double tube pneumatic tires and the primary object of the invention resides in the means employed for holding and locking the sections of the core body in assembled relation, said means being effectual for the purpose, easily applied to permit the ready assembling of the core and capable of being moved quickly circumferentially of the core body to permit the collapsing of the same.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures, Figure 1, is a plan view of a core assembled embodying this invention; and, Fig. 2 is a transverse sectional view on line X, X of Fig. 1.

A ring core embodying this invention is customarily constructed of a plurality of segment-shaped sections which when united together as hereinafter described, constitute an annulus, the outer and lateral faces of which are shaped to impart a preferred configuration to the corresponding inner face of the tire or tire shoe which is to be manufactured thereon.

The sections which are employed to form the annular core are designated in the drawings by the reference numerals 1, 2, 3 and 4 and are each provided with inwardly-extending flanges 5. These flanges are all similar and are provided on their inner lateral faces with laterally-projecting ribs 6 connected with the flanges 5 by inclined shoulders 7. The members 1 and 4 are provided at the ends thereof with projecting

ribs 8 and the ends of the members 2 and 3 are provided with complementary grooves 9 into which the ribs are adapted to engage for effecting complete registration between the several parts of the core when assembled. The junction lines 10 between the ends of the section 1 and the sections 2 and 3 are so inclined that the member 1 is substantially wedge-shaped to constitute a key member. The joints between the sections 2, 3 and 4 are approximately radial with respect to the assembled core.

The means employed in this invention for holding various sections in assembled relation to constitute an annular core body comprise a pair of clamping members adapted to overlap the abutting ends of the flange of various sections for holding them in complete registration and as the means employed at each joint are identical a description of one set is believed to be sufficient for the understanding of all. Each of these clamping means embodies a member 11 of sufficient length to overlap a considerable portion of the flanges of abutting sections and provided on the face which opposes the core with an inwardly-extending rib 12 provided with one inclined edge 13 which is adapted to engage one inclined shoulder 7. The member is further provided with a longitudinally-extending groove 14 which freely receives the rib 6 of the flange. The inner portion of the member 11 is provided with an aperture 15. The companion member 16 of the clamp is provided on the face which opposes the core body with an inwardly-projecting rib 17 having one inclined edge 18 to coact with the shoulder 7 of one rib 6 and is further provided with a groove 19 to receive one rib 6. The inner portion of the member 16 is provided with a threaded aperture 20 arranged in alignment with the aperture 15. Positioned in the aligned apertures is a cap-screw 21 constituting means for clamping the two members 11 and 16 against the side face of the ribs 6 of the flanges 5. The core is assembled by placing the various sections in assembled relation and then positioning the clamping members 11 and 16 so that they overlap the joints between contiguous sections and by tightening the cap screws 21 the sections are held in perfect circumferential alignment.

When it is desired to dismantle the core the cap-screws are loosened sufficiently to permit the clamping device to be shifted cir-

2 cumferentially away from the joints in the sections as indicated in dotted lines in Fig. 1 and designated by the reference numeral 22, so that it is not necessary to entirely remove the clamp, but only to remove the screws sufficiently to permit these members to be slid away from the joints after which the core may be collapsed in the ordinary manner now employed with reference to 10 cores of this general type. It will be obvious that instead of a cap screw 21 an ordinary bolt may be employed and in such cases the aperture 20 is not threaded but extends entirely through the member 16.

15 I claim:—

1. A collapsible core for the manufacture of tire shoes or casings comprising a series of segment-shaped sections adapted to be assembled into a circular core with their 20 ends abutting against each other and each section formed with an inwardly-extending flange, and a pair of clamping members applied to opposite sides of the flanges of the core sections at the joints between said sections, said clamping members comprising a pair of members with their inner faces fashioned to conform to the shape of the sides of the flanges in contiguous sections and of sufficient length to overlap said ends, 30 and means connected with said clamping means for drawing them toward each other for clamping the sections in assembled relation, said clamping means arranged when loosened to permit the circumferential shifting of the clamping members on the core flanges away from the joints between sections to allow of the collapsing of the core.

2. A collapsible core for the manufacture of tire shoes or casings comprising a series 40 of segmental shaped sections adapted to be assembled into a circular core with their ends abutting against each other and each section formed with an inwardly extending flange, said flanges provided on opposite 45 sides with lateral and circumferentially-extending ribs, a pair of clamping members provided on their inner opposing faces with

grooves to receive said ribs and interlock therewith, said clamping members arranged to be applied to the flanges of the core at 50 the joints between contiguous sections and of sufficient length to overlap portions of the ends of the flanges, and means extending in said clamping members for drawing them toward each other to clamp the flanges 55 of the sections and hold them in assembled relation, said means arranged when slightly loosened to permit the circumferential shifting of the clamping members circumferentially of the core body to permit the 60 collapsing of the core.

3. A collapsible core for the manufacture of tire-shoes or casings comprising a series of segment-shaped sections adapted to be assembled into a circular core with their 65 ends abutting against each other, said section provided with inwardly-extending flanges, said flanges provided with lateral and circumferentially-extending ribs, the outer edges of said ribs being inclined, a 70 pair of clamping members adapted to be applied to and overlap opposite faces of the contiguous ends of said flanges, said clamping members provided with longitudinally-extending grooves to receive said ribs, one 75 of the walls of each of said grooves inclined to coact with the inclined edges of said ribs, clamping means extending in the clamping members for drawing them toward each other for clamping the sections together into annular formation, said clamping means adapted when slightly loosened to permit the circumferential shifting of the clamping members circumferentially of the 80 core body to permit the collapsing of the 85 core.

In testimony whereof I have hereunto set my hand in presence of two subscribing witnesses.

ALEXANDER ADAMSON.
